US00D609459S

(12) **United States Design Patent**
Ferren et al.

(10) **Patent No.:** **US D609,459 S**
(45) **Date of Patent:** **** Feb. 9, 2010**

(54) **EXPANDABLE BACKPACK**

(75) Inventors: **Michael C. Ferren**, Seattle, WA (US);
Michael A. Valencia, El Dorado Hills, CA (US)

(73) Assignee: **Michael Valencia**, El Dorado Hills, CA (US)

(**) Term: **14 Years**

(21) Appl. No.: **29/280,176**

(22) Filed: **May 18, 2007**

(51) **LOC (9) Cl.** **03-01**

(52) **U.S. Cl.** **D3/217; D3/216; D3/270**

(58) **Field of Classification Search** **D2/830; D3/214, 215, 216, 217, 270; 224/153, 577, 224/578**

See application file for complete search history.

(57) **CLAIM**

We claim the design for an expandable backpack, as shown.

DESCRIPTION

FIG. 1 is a front perspective view of an expandable backpack showing our new design;

FIG. 2 is a front perspective view thereof showing an expansion section opened;

FIG. 3 is a bottom view thereof;

FIG. 4 is a top view thereof;

FIG. 5 is a left side view thereof;

FIG. 6 is a right side view thereof;

FIG. 7 is a front view thereof; and,

FIG. 8 is a rear view thereof.
